EXAMINER'S TRACING

UNITED STATES PATENT OFFICE.

ALFRED HEALD, OF PHILADELPHIA, PENNSYLVANIA, ASSIGNOR TO HUGH McCALLUM, ORLANDO CREASE, ANDREW J. SLOAN, AND WILLIAM McCALLUM, OF SAME PLACE.

DESIGN FOR CARPET.

Specification forming part of Design No. 7,440, dated May 19, 1874; application filed May 8, 1874.
[Term of Patent 3½ years.]

CASE W.

To all whom it may concern:

Be it known that I, ALFRED HEALD, of Philadelphia, Pennsylvania, have invented a Design for a Carpet-Pattern, of which the following is a specification:

The accompanying drawing clearly illustrates my design for a carpet-pattern, the principal features of which are the large figures A. Each of these figures has a central ornament, a, composed of leaves arranged radially, and the border b, which defines the shape of the figure, consists of an ornamental band caused to take the angular course represented. Wide checkered bands d d extend transversely across the projecting portions of the figure at four different points, and the said figure is otherwise ornamented, as shown. The spaces B

and D between the figures are elaborately ornamented by flowers, leaves, stems, &c., all of the character clearly shown in the drawing.

Irrespective of the colors employed, I claim—

1. The design for the figure A, as described and represented.

2. The design for the whole pattern, including the figures A and ornamental spaces B and D.

In testimony whereof I have signed my name to this specification in presence of two subscribing witnesses.

ALFRED HEALD.
